(57) **CLAIM**

The ornamental design for a motorcycle tire, as shown and described.

DESCRIPTION

FIG. 1 is a perspective view of a motorcycle tire showing my new design;

FIG. 2 is a front view thereof;

FIG. 3 is a top view thereof;

FIG. 4 is a right side view thereof;

FIG. 5 is a fragmentary enlarged front view

FIG. 6 is an end view taken along line 6-6 in FIG. 5; and, FIG. 7 is an end view taken along line 7-7 in FIG. 5.

Broken lines shown in the drawings show portions of the motorcycle tire that form no part of the claimed design. The light stippled surface shading is the surface of the motorcycle tire, and the dark stippled surface shading is the recessed portion of the tread grooves, having the depth as shown in FIGS. 6 and 7.
